UNITED STATES PATENT OFFICE.

THOMAS J. BROOKS, OF NASHVILLE, TENNESSEE.

ILLUMINATED WRITING IMPLEMENT.

Application filed January 25, 1926. Serial No. 83,629.

This invention relates to attachments for pens, pencils and the like, an object being to provide means whereby an electric lamp may be removably attached to a writing implement whereby the latter may be conveniently used in dark places.

Another object of the invention is the provision of means whereby an electric lamp may be attached to a writing implement so as to project its rays of light to the point of the implement and at the same time shield the eyes of the user.

Another object of the invention is the provision of an electric lamp attachment for writing implements having novel and convenient means for controlling a circuit through the lamp.

With the above and other objects in view, the invention further includes the following novel features and details of construction, to be hereinafter more fully described, illustrated in the accompanying drawings and pointed out in the appended claim.

In the drawings:—

25 Figure 1 is an elevation of a pencil with the invention applied.

Figure 2 is an enlarged longitudinal sectional view of the invention per se.

30 Figure 3 is an enlarged section on the line 3—3 of Figure 2.

Figure 4 is a similar view on the line 4—4 of Figure 2.

Referring to the drawings in detail wherein like characters of reference denote corresponding parts, it may be here stated that while the invention is shown as applied to a pencil indicated at 10, it may be attached to a pen, a firearm, or to various other implements or devices.

40 As shown in the drawing, the invention comprises a tubular casing 11 which is open at one end and this open end is beveled so that an electric light bulb 12 may be carried within the casing sufficiently close to the outer end of the latter to provide a maximum amount of light at the point of the pencil and at the same time shield the eyes of the user.

Secured within the casing is an insulating 50 cylinder 13 which is provided with a socket 14, the latter having secured therein an electric lamp socket 15. Connected to one terminal of the socket is a conductor 17 to which is secured an electric conductor wire

18, while connected to the other terminal of the socket is a conductor 19 having a conductor wire 20 attached thereto. The conductor wires 18 and 20 are adapted to lead to a suitable source of current, such as a small dry cell capable of being carried in the 60 pocket of the user.

The conductor 19 is interrupted so as to provide a space or gap 21 which is adapted to be bridged by spring contact arms 22 which are secured to and extend in opposite 65 directions from an insulating block 23. This block 23 is slidable transversely of the cylinder 13 and has extending from opposite sides buttons 24 which project through openings provided in the casing 11. The block 70 may be moved transversely of the conductor 19.

By reference to Figures 2 and 3 of the drawings it will be seen that by moving the block transversely the spring contact 75 fingers may be engaged with the adjacent ends of the conductor 19 so as to bridge the space or gap provided in the latter and complete a circuit through the lamp 12. When the block 23 is in the position shown in Figure 3 of the drawings, circuit through the lamp will be interrupted.

The conductors 17 and 19 are secured in place by means of pins 25, while a pin 26 holds the spring contact fingers 22 to the 80 block 23.

The conductors 17 and 19 carry at their outer ends clips 27 for connection with the conductor wires 18 and 20.

Extending from the casing 11 are spaced 85 pairs of oppositely extending curved gripping fingers 28 which are adapted to engage around the pencil 10 to hold the device in place.

The invention is susceptible of various 90 changes in its form, proportions and minor details of construction and the right is herein reserved to make such changes as properly fall within the scope of the appended claim.

Having described the invention what is claimed is:—

A device of the class described comprising a tubular casing open at one end, a socketed insulating cylinder within one end of the casing, a lamp socket within said cylinder, an electric lamp within the socket, means including an interrupted conductor 105

whereby the current may be supplied to the lamp, an insulating switch block movable transversely of the interrupted conductor, oppositely extending spring contact fingers carried by the block, means whereby the block may be moved to move the contact fingers into and out of contact with the inter- rupted conductor for controlling the flow of current through the latter and means whereby the device may be removably secured in position for use. 10

In testimony whereof I affix my signature.

THOMAS J. BROOKS.
